UNITED STATES PATENT OFFICE.

ANNA NORAS, OF BUFFALO, NEW YORK.

SUSPENDERS.

1,119,716.

Specification of Letters Patent.

Patented Dec. 1, 1914.

Application filed March 25, 1912, Serial No. 685,913. Renewed April 30, 1914. Serial No. 835,541.

To all whom it may concern:

Be it known that I, ANNA NORAS, a citizen of the United States, residing at Buffalo, in the county of Erie and State of New York, have invented certain new and useful Improvements in Suspenders, of which the following is a specification, reference being had therein to the accompanying drawing.

This invention relates to suspenders, and 10 has special reference to attaching tabs which are supported thereby.

The object of this invention is the production of an efficient trouser engaging end which consists of a pair of supporting members, one member being placed within the other so as to furnish efficient supporting means for trousers especially where a pair of trousers, such as overalls or the like are worn over the ordinary trousers.

20 Another object of this invention is the production of efficient means for firmly holding the inner trouser supporting end within the outer trouser supporting end and also efficiently reinforcing the under face 25 of the trouser supporting ends.

With these and other objects in view this invention consists of certain novel constructions, combinations, and arrangements of parts as will be hereinafter fully described 30 and claimed.

In the drawings:—Figure 1 is an elevation of a pair of suspenders embodying this invention. Fig. 2 is a detail perspective of one of the trouser supporting ends. Fig. 3 is a side elevation of the portion of the end showing the supporting loop in section. Fig. 4 is a transverse section through the tubular portion of the supporting ends.

Referring to the drawings by numerals 1 40 designates the usual suspenders which carry the front and rear end engaging loops 2. The ends 3 comprise an outer section 4, and an inner section 5, each of said sections being provided with the usual button engaging loops or tabs 6. The inner and outer sections of the ends 3 are rolled so as to form a substantially tubular body as clearly illustrated in Fig. 4, and the edges of said ends are firmly held together through the medium 45 of the reinforcing strands 7. These strands are sewed through the tubular portion of the inner and outer sections near their adjacent ends as illustrated in Fig. 4, and cross each other upon the under face of the 50 tubular portion thereby greatly reinforcing

the tubular portion of the ends upon their under side. It will, therefore, be obvious that a very efficient wearing surface has been produced for the ends since the reinforcing threading members, which may be 60 made of very tough strands, form a protecting medium for the under or wearing face of the ends. It will be seen by giving Fig. 2 very careful consideration that the inner end 5 merges into the outer end 4 so 65 as to conform to the shape thereof and form a very smooth and unobstructed button-engaging flap upon the outer ends thereof.

From the foregoing description, it will be 70 readily obvious that a very efficient suspenders has been produced, the ends of which may be readily assembled and, at the same time, present a pair of button engaging loops or tabs upon each end of said ends, one of said loops being placed within the 75 other. Of course, after the ends are cut to the desired shape, one end is placed within the other, and by merely rolling the body or tubular portion and stitching the same no additional securing means will be 80 found necessary to hold the ends in their relative position. Furthermore through the medium of the securing means above described, the inner section will not have a 85 tendency to pucker, in view of the fact that the outer section is formed so as to allow the button engaging loop of the inner section to merge or become seated within the loop of the outer section.

What is claimed is:

90 A suspender end of the class described comprising inner and outer tubular sections, each provided with tabs, said inner section having its tubular body portion fitting within the tubular body portion of said outer section, cross stitches or reinforcing strands firmly binding the edges of said inner and outer sections together, to make a tubular body for said end and acting as a protecting means for the under edge of said tubular body portion, and the tabs of said outer section being so formed as to allow the tabs of said inner section to merge into the tubular portion of said outer section.

95 In testimony whereof I hereunto affix my 100 signature in presence of two witnesses.

ANNA NORAS.
